FIG. 1.

FIG. 2.

FIG. 3.

INVENTOR

HUGH C. McWILLIAMS,

BY H.B. Wilson & Co.

ATTORNEY

UNITED STATES PATENT OFFICE

164,699

SUNMASK

Hugh C. McWilliams, San Antonio, Tex.

Application July 9, 1951, Serial No. 15,791

Term of patent 7 years

(Cl. D57—1)

To all whom it may concern:

Be it known that I, Hugh C. McWilliams, a citizen of the United States, residing at 940 W. Huisache Street, San Antonio, State of Texas, have invented a new, original, and ornamental Design for a Sunmask, of which the following is a specification, reference being had to the accompanying drawing, forming a part hereof.

Fig. 1 is a perspective view of a sunmask showing my new design;

Fig. 2 is a top view; and

Fig. 3 is a side view.

I claim:

The ornamental design for a sunmask, as shown.

HUGH C. McWILLIAMS.
